CLAIM

The ornamental design for an electronic bath control cover, as shown and described.

DESCRIPTION

FIG. 1 is a left front perspective view of an electronic bath control cover showing my new design;

FIG. 2 is a front view of the cover thereof;

FIG. 3 is a left side view of the cover thereof, the right side view being a mirror image of the left side; and,

FIG. 4 is a top plan view of the cover thereof.

1 Claim, 4 Drawing Sheets

FIG. 1

FIG. 2

FIG. 3

FIG. 4
